United States Patent Office

Des. 199,058
Patented Sept. 8, 1964

199,058

CHAIR

Robert E. Kjer Jakobsen, Manhattan Beach, Calif., assignor to Schlumberger Limited (Schlumberger N.V.), Houston, Tex., a corporation of the Netherlands Antilles

Filed Mar. 31, 1964, Ser. No. 79,271

Term of patent 14 years

(Cl. D15—1)

FIG. 1 is a rear perspective view of a chair, showing my design;

FIG. 2 is a side perspective view thereof;

FIG. 3 is a front perspective view thereof; and

FIG. 4 is a bottom perspective view thereof taken from the front with portions cut away for convenience of illustration.

I claim:

The ornamental design for a chair, substantially as shown.
